UNITED STATES PATENT OFFICE.

JAMES ELIA, OF CHICAGO, ILLINOIS.

HANDLE-SWITCH.

1,127,973.

Specification of Letters Patent.

Patented Feb. 9, 1915.

Application filed November 13, 1911. Serial No. 660,095.

To all whom it may concern:

Be it known that I, JAMES ELIA, a citizen of the United States, and a resident of the city of Chicago, county of Cook, and State of Illinois, have invented certain new and useful Improvements in Handle-Switches, of which the following is a specification.

My invention relates to improvements in handle switches for metal finishing or buffing machines and has for its object the production of a device of this character which will be of a simple nature, one which will be durable and economical in construction and efficient in use.

Other objects will appear hereinafter.

With these objects in view my invention consists in the novel combination and arrangement of parts hereinafter described and claimed.

My invention will be best understood by reference to the accompanying drawing forming a part of this specification, and in which,

25 Figure 1 is a sectional side elevation of a buffing tool embodying my invention, and Fig. 2 is an enlarged sectional detail illustrating the connection of the handle with the motor of the device.

30 The preferred form of construction as illustrated in the drawing comprises a substantially cylindrical handle 1 formed of an insulating or non-conducting material, preferably wood. Secured to and projecting from one end of the handle 1 is a substantially cylindrical metallic cap 2, the front end of said cap being closed. Secured, as by soldering, to the front end of the cap 2 is a screw threaded plug 3 similar to the 35 plug of an ordinary electric light globe. The metallic casing of the plug 3 which, when the device is in use, serves as an electrical conductor of the electric current from the conductor wires to the motor herein- 40 after described, is formed with a rearwardly projecting arm 4, said arm projecting through a perforation 4' formed in the end of cap 2 and being connected with one of the conductor wires 5 which project through 45 longitudinal passages 6 provided for the reception thereof in the handle 1; said wires projecting to and being connected with any suitable source of electrical energy. The 50 contact 7 provided at the outer end of the plug 3 and which is insulated from the metallic casing of the latter, is connected with

the forward end of a rearwardly projecting spring arm 8, said arm projecting through a perforation 8' provided in the end wall of cap 2. Mounted on the forward end of the handle 1 within the cap 2 is a spring arm 9 which is connected as shown with the other of the conductor wires 5. The arms or contacts 8 and 9 are electrically connected through the medium of a sliding switch member 10. The member 10 is provided at its outer end with an exteriorly projecting button 11 of insulating material, the opening 12 in the cap 2 which permits of the passage of said button being elongated in order to permit of sliding movement thereof for making and breaking the connection between the contacts 8 and 9. The button 11 is provided at its base with a circumferential flange 11' which engages against the inner side of the adjacent wall of cap 2, the resiliency of the spring member 9 serving to force the member 10 outwardly so that the flange 11' forcibly engages against said inner surface of said cap, thereby serving to frictionally maintain the switch member 10 in any position to which the same may be adjusted. The button 11 is so positioned as will be observed, that the same may be readily engaged by the thumb of the operator for readily making or breaking the motor circuit.

Arranged at the forward end of the handle 1 is an electric motor 13 of any ordinary or preferred design. The stationary casing 90 of the motor 13 is provided at the side thereof adjacent the handle with a socket formed of the outer casing 14 rigidly secured as by bolting to said motor casing, the inner screw-threaded metallic lining 15, and the 95 intermediate layer of porcelain or other suitable insulating material 16. Said socket is detachably engaged by the plug 3 of the handle 1, the threads of said plug being adapted to engage with the threads of lining 15. The motor and handle are securely locked together by means of a set screw 17 threaded in an ear 18 formed upon the cap 2, the inner end of said screw being adapted to engage against the adjacent side of the 100 socket casing 14 as clearly illustrated.

Projecting inwardly from the metallic casing 16 of the socket is a spring contact arm 19 adapted to engage one of the terminals 20 of the motor, a contact 21 mounted in a cup-like bearing member 22 formed of insulating material engaging the other

terminal 23 of the motor at its inner end, the outer end of the contact 21 being positioned for engagement with the contact 7 of the plug 3. The member 23 is formed as shown in order to adapt the same for service as a bearing for the adjacent extremity of the driven shaft 24 of the motor.

With the construction set forth it will be seen that the current from the source of 10 electrical energy will pass through one of the conductor wires 5 to arm 4, thence to the metallic outer wall of plug 3 to metallic lining 15 of the socket, whence the same will pass through contact 19 to terminal 20 of 15 the motor. From the motor the current will pass from terminal 23 to contact 21, thence to contact 7, arm 8, through switch member 10, arm 9, and thence through the return conductor wire 5 to the source. The 20 circuit thus constituted is controlled by the switch 10 and may be made or broken by simply engaging and moving the button 11.

While I have illustrated and described the preferred form of construction for carrying 25 my invention into effect, this is capable of variation and modification without departing from the spirit of the invention. I, therefore, do not wish to be limited to the precise details of construction set forth, but 30 desire to avail myself of such variations and

modifications as come within the scope of the appended claim.

Having described my invention what I claim as new and desire to secure by Letters Patent is:

An electrical switch comprising a casing 35 having a slot therein; a switch member extending through said slot and longitudinally slidible on said casing, said switch member having a shoulder against the inner side of 40 said casing; a button on the outer end of said switch member engaging the outer side of said casing; a spring contact member in said casing parallel with the path of movement of said switch member and constantly 45 pressing against the inner end of said switch member; the inner end of said switch member being off-set and provided with a beveled face and a second contact member in said casing and having an inclined end 50 adapted to be engaged by said beveled face of said switch member to close said switch, substantially as described.

In testimony whereof I have signed my name to this specification in the presence of 55 two subscribing witnesses.

JAMES ELIA.
